UNITED STATES PATENT OFFICE.

WASHINGTON I. FITCH, WILLIAM WILSON WEISELL, AND LEE S. KAPP, OF BLUFFTON, INDIANA.

WASHING-MACHINE.

SPECIFICATION forming part of Letters Patent No. 375,278, dated December 20, 1887.

Application filed June 10, 1887. Serial No. 240,932. (No model.)

To all whom it may concern:

Be it known that we, WASHINGTON I. FITCH, WILLIAM WILSON WEISELL, and LEE S. KAPP, citizens of the United States, residing 5 at Bluffton, in the county of Wells and State of Indiana, have invented certain new and useful Improvements in Washing-Machines, of which the following is a specification, reference being had therein to the accompanying 10 drawings.

This invention relates especially to washing-machines in which the tub is a frustum of a cone and the fastening-hoops are driven from above downward over the same.

15 It is well known that in this class of machines the hoops will slip upward when the tub is dry. Our object is to prevent the displacement of the hoops by means of a novel device, which will also afford a rigid attachment for the supporting-legs and binders therefor and stop-lugs at their upper ends, as 20 will be more fully hereinafter set forth.

25 This device is illustrated in the annexed drawings, which, taken in connection with our specification and claim, will be fully understood.

In the annexed drawings, Figure 1 is a perspective view of the washing-machine, showing clearly our invention applied thereto. 30 Fig. 2 is a perspective view of the device detached from the tub, and Fig. 3 is a section taken vertically through the device and one of its shouldered parts holding the upper hoop.

35 Referring to the annexed drawings by letters, A designates a tub for a washing-machine, which is the frustum of a cone and composed of a number of staves bound together by hoops *a a* in the usual well-known manner.

40 We have found in practice that when the tub is dry the hoops will become loose and the wood will shrink from the hoops. For the purpose of obviating this objection we employ a device which will not only afford a socket for the upper end of a sustaining-leg, but which will 45 also afford an upper bearing for this leg and a

binder for the hoops. This device we will now describe.

B designates the improved socket, which is of skeleton form and constructed as follows: 50 The main frame of this leg attachment is composed of upright bars *d d*, which are constructed with shoulders *e e*, adapted to afford bearings against the hoops *a*, over which the outwardly-bowed portions *f f* pass freely. 55 This frame is also constructed with transverse bowed portions or loops *g g*, and also with cross-bars *g'*, from the face of the upper one of which lugs *n n* protrude. The transverse end bars, *g'*, which hug the tub and the upper and 60 lower ends of the frame B, are perforated and adapted to receive screws *s s*, which rigidly secure the device to the tub. These transverse bars are integral with the arched or bowed portions *g g*, which latter are preferably angular, for the purpose of receiving the legs G, which are angular in cross-section and beveled at their upper ends. These legs, 65 which are of wood, are received in the socket between the metal skeleton portion of the 70 frame and its loops *g*, and their upper ends abut against the lugs *n n* to prevent upward displacement. These legs thus wedge themselves in the brackets, and they have a tendency to press the shoulders of those portions 75 of the said frame which bear against the body of the tub closely against the outer surface of the tub above and below the binding-hoop *a*. It will thus be observed that the legs, combined with the brackets, co-operate to hold 80 the hoop in its place, while at the same time the said bracket will hold the leg in its place.

It will be observed that the upper outer edges of the legs are beveled at *i*, for the purpose of enabling the same to be readily inserted in the socket. It will also be observed that the lower hoop or bowed portion, *g*, of the frame is perforated at *n'*, through which perforation a screw is passed, the screw entering the leg and serving to hold it in place in the 85 socket.

Having thus fully described our invention,

what we claim as new, and desire to secure by Letters Patent, is—

The combination, with the hoop-bound wash-tub and legs, of the sockets B, secured to the tub, each of said sockets consisting of a main frame provided with shoulders for abutting against the hoops to hold them in position on the tub, lugs against which the upper ends of the legs abut, and the arched loops for holding the legs, substantially as described.

In testimony whereof we affix our signatures in presence of two witnesses.

WASHINGTON I. FITCH.
WILLIAM WILSON WEISELL.
LEE S. KAPP.
